R. G. Kirkwood
By his Atty, A. D. Griffith

UNITED STATES PATENT OFFICE.

ROBERT G. KIRKWOOD, OF ELLICOTT CITY, MARYLAND.

WIND-WHEEL.

SPECIFICATION forming part of Letters Patent No. 278,561, dated May 29, 1883.

Application filed April 27, 1882. (No model.)

To all whom it may concern:

Be it known that I, ROBERT G. KIRKWOOD, of Ellicott City, Howard county, in the State of Maryland, have invented a new and useful Improvement in Wind-Wheels; and I do hereby declare that the following is an accurate description of the same.

My invention relates, first, to the structure of the supporting-frame; second, to the structure 10 of the wheel-frame; third, to the structure of the wheel; fourth, to the structure of the governing device; fifth, to the structure of the tail-vane; and the particular matters of structure will be pointed out in the following 15 description and claims annexed.

Figure 1 is a perspective view of my wheel. Fig. 2 is a horizontal or plan view of the tail-vane, showing its connection with the tubular frame. Figs. 3 and 4 are sectional details of 20 the wheel.

The principal or base support for my wheel may be constructed in any proper manner. That part of the working structure does not enter into this invention. The immediate support of the wheel and its mechanism is a tubular post, A.

A' is a post upon which the mechanism of the device is mounted.

B is a lug, having a central opening adapted 30 to receive the tube A. Lug B is provided with arms or a rectangular band, by means of which it is rigidly united to post A'. B' is also a lug rigidly fixed to post A', and it is provided with a central opening adapted to receive the tube A.

35 b is a collar or flange-ring rigidly fixed to tube A, and b' is a flange-plate formed integral with ring b. The weight of the wheel is centered on the ring b. Said ring has a bearing on the upper face of lug B. The arms of the wheel-frame C rotate freely on tube A. The flange-plate b' serves as a partial bearing for the lower wheel-arm. Said plate also serves as a stop for said lower arm.

40 A² is a collar provided with a flange-plate, A³, said collar and flange being rigidly united to tube A.

The frame C is a single tubular hub with two lateral arms, e e, and perforated lugs f f at their extremities, through which the tube A 45 passes when the parts are in working position to form a pivot whereon the wheel may swing through one-fourth of a circle, nearly, to bring its face or edge to the wind. The tubular hub portion of the frame C constitutes the bearing

for the shaft G of the wheel H. The inner end 55 of the shaft G bears the crank-wheel I, and thereby drives the pitman J. The upper end of this pitman passes through a slot, a, in the lug f, and engages with an arm, d, which extends laterally from the upper end of the tubular piston-rod K, which descends through 60 the tube A to transmit motion from the shaft G to the driven mechanism below. In order to prevent any rotary movement of the piston-rod K on its own axis, the extremity of the arm 65 d moves up and down in a slotted plate or loop, g, erected on the lug f.

The wheel H has a solid center, i, secured 70 rigidly to the end of the shaft G, and from said center a series of arms, h, radiate. The number of these arms is greater or less, according to the size or purpose of the wheel. Two rimstrips, j k, of metal, are mounted upon said arms, the former at their extremities and the latter at an intermediate distance. Lateral 75 pieces l are attached to the arms at the points of attachment of the strips j k, and as a matter of fact I prefer to constitute these pieces the means of attachment, the strips j k being riveted to said strips l, and the ends of the latter, m m, are bent over for convenient attachment by screws with the sides of the arms, as shown. This particular method is not essential, however. The pieces l extend backward toward the frame C, and at their extremities 80 they bear other rim-strips, r s, and the flat sheet-metal vanes L are secured between these front and rear rim-strips, as shown, the front edges being strengthened by attachment to the arms h. The vanes L may be further 85 strengthened and braced by strips p. The inner strips, k s, may be united and formed from a single sheet, if desired, and the same may be said of the outer strips, j r; but my preference is to make them separate, as shown, and thus 90 render the wheel lighter. By this method of construction the working-surfaces of the wheel are all in rear of its point of attachment to its shaft, and the latter is thereby relieved of 95 the wrenching strains inseparable from the location of the working-surfaces in front of said point of attachment.

This invention belongs to that class of wheels known as "flexible tail-vane wheels," wherein there is a pivotal connection between the tail-vane and the wheel-frame, so that while the tail-vane is in the wind's plane the wheel may assume a position parallel or transverse there-

to, or be placed at any intermediate angle of obliquity. In this case I have shown a rigid connection between the tail-vane and the tube A, and I prefer to construct it in that way, yet it is not a necessary mode of structure, because the tail-vane might be caused to revolve on said tube as well as on the wheel-frame.

In order to govern and control the wheel, a small side vane, M, is employed, which presents its face to the wind when the wheel presents its face to the wind, and it is so geared to the wheel-frame that as the force of the wind increases and surpasses a certain predetermined force said side vane will be pressed back and cause a corresponding movement of the wheel on its pivotal support A, so as to present its edge more and its face less to the wind, and thereby reduce the exposure of working-surface. In this wheel the side vane, M, is mounted on a pivot, q, which projects from the lug f, and it is provided with a segment-pinion, r', which meshes with a corresponding segment-pinion, s, which is attached to the tail-vane frame, in this case constituted by the tube A. As the side vane, M, swings backward on its pivot q it causes a corresponding movement of the wheel H in the opposite direction, and when said vane has passed around until it is parallel with the tail-vane the plane of the wheel will also be parallel with the tail-vane, and will then present its edge to the wind and come to rest. The resistance or governor to prevent this movement taking place whenever the wind blows is a counter-weight applied to the side vane. In this instance said weight is shown at N. A backward movement of the tail-vane will raise said weight, and is there resisted by its gravity, and the weight is therefore adjustable or subject to increase or diminution of effect in some way, so that the power developed by the wheel may be in some way under control. When it is desired to stop the wheel or hold it at rest the tail-vane M is forcibly pulled around, and the wheel is thereby brought edge to the wind, and this is accomplished at pleasure by a cord, t, which extends from some proper part of the arm of the side tail-vane over a swiveled pulley, u, and down through the tubular frame A to a point convenient to the hand of the attendant. The pulley u may be supported by a post, v, erected upon the segment s, or otherwise attached to the tail-vane frame M.

The tail-vane D is composed of sheet metal, and it is supported by two converging arms, P, which have their forward ends secured at the extremities of the arms of plate b. At their rear ends the arms P are secured in a double cap, w, and at intermediate points they are supported by ties y y, and at mid-points the ties y y have attached to them brace-pieces z, to which the vane D is riveted and supported. The arms P give the vane its lateral support, and it is supported vertically by the string-rod Q.

The plate b' is provided with a flange, R,

which serves as a stop to limit the movement of the wheel and its frame.

It will be observed that the frame-work of this machine is largely constructed of ordinary pipe and connecting-thimbles, &c. The parts A K P and arms of the side vane are so composed. This greatly facilitates and cheapens the construction.

Having now described my invention, what I claim as new is—

1. The post A', having lugs B B', rigidly secured thereto, in combination with the tubular rotating pivot A, provided with rigid collar b and stop-plate b', substantially as described, and for the purposes set forth.

2. The post A', having lugs B B', rigidly secured thereto, and the tubular rotating pivot A, provided with collar b and stop b', rigidly secured thereto, in combination with the tubular hub C, arms e e, and collar-arms f f, the lower arm f being provided with a lug adapted to engage the stop-lug on the flange-plate b', as set forth.

3. The wheel H, shaft G, crank-wheel I, supported by hub C, and the pitman J, in combination with the upper arm f of the wheel-frame, provided with slot a and guide rods or loop g, and the piston-rod K; provided with lateral arm d, whereby said piston-rod is prevented from rotating, substantially as described, and for the purposes set forth.

4. The gear s, mounted on tube A, and provided with standard v and pulley u, in combination with rope t, weight N, gear r', and side vane, M, the vane M and gear r' being united by rod upon which the weight N is mounted, substantially as and for the purposes set forth.

5. The wheel H, provided with shaft G, rigidly attached thereto, and the hub C, having arms e e f f, formed integral therewith, in combination with the tubular pivot A, provided with collar b, having flanged stop-plate b', and the collar A², provided with flange-plate A³, and the tail D, supported by rods P Q, the tube A, collars b A², plates b' A³, rods P Q, and tail D being rigidly united, as set forth.

6. The wheel H, constructed with the solid center i, and the arms h h, extending radially therefrom, and the rim-strips j k, secured thereto, as described, combined with the strips r s, supported in rear of said arms by the piece l, and the sheet-metal vanes L, attached substantially as set forth.

7. In a wind-wheel provided with metallic rim, the sheet-metal vanes re-enforced with diagonal strips P, riveted fast to said vanes, as set forth.

8. The converging stays P, secured at their front ends to the cross-plate b, and their rear ends to the cap-piece w, combined with the intermediate cross-bar, y y, and the brace-strips z, to support the vane D, as set forth.

R. G. KIRKWOOD.
